TELEVISION SYSTEM

Cecil N. Batsel, Camden, N. J., assignor to Radio Corporation of America, a corporation of Delaware

Application January 10, 1941, Serial No. 373,874

1 Claim. (Cl. 178—7.1)

This invention relates to television systems, and more particularly, to improvements in studio practice and technique in the production of television programs for transmission.

In presenting television programs, it is necessary that there be no delay in changing from one scene to another during the transmission. Television production technique, therefore, is quite different from that of motion picture practice where the taking of the various scenes need not necessarily follow the final order of presentation and where time between the photographing of scenes is of no consequence in regard to the final edited film. Moreover, the television transmitting system requiring so much more apparatus than motion picture work does not lend itself economically to the use of as many television cameras, and chains, as one may use in motion picture practice. It is generally desirable to have at least two cameras and, preferably, three cameras, equipped with varying focal length lenses in a television production. The cameras are located at different angles with respect to the scene being televised, in order to supply a variety of "shots," which is necessary to maintain the viewer's interest.

It will be readily apparent that under these circumstances in a production, where several scenes must be televised, difficulties are met in first being able to change scenes rapidly, and secondly, where separate scenes can be set up in advance in providing sufficient numbers of cameras to be trained upon the scene which is to be televised, following the televising of a preceding scene. In order to overcome these difficulties, and to provide a rapid means of televising a series of scenes in sequence with a minimum amount of camera equipment, my invention proposes to mount the cameras in a central location to provide a plurality of scenes in a circle around the central location, and to afford relative rotational movement between the cameras and the scenes. By having the scenes laid out along radial lines, the shifting from one scene to another may be readily accomplished without any substantial loss in time. At the same time, only a minimum number of cameras are required for the purpose of affording the necessary variety of different views of a single scene. Background projection may be utilized to augment the scenic effects by providing translucent projection screens to the rear of the scene. Loud speakers may also be located to the rear of the screens for accompanying sound effects. By such a plan, the various scenes may be set up beforehand or even during the televising of one of the other scenes. By this arrangement, since the distances from the center camera location are substantially the same for all scenes, the televising of sequential scenes does not entail any loss of time arising from the necessity of refocusing the

cameras. All of these features lead to smoother and improved television studio technique with an over-all gain in the entertainment value of the television pictures received at the receiving point.

Accordingly, it is the main purpose of the present invention to provide an improved television studio technique. Another important feature of my invention is to reduce the amount of time required to change from televising one scene to a sequential scene.

A further object of my invention is to reduce the number of television cameras required for televising a series of sequential scenes to a minimum.

Another object of my invention is to provide improved studio technique in televising programs by providing background projection and accompanying sound effects in a simple, efficient manner.

Other objects of my invention will become apparent upon a reading of the following description taken together with the drawing.

In the drawing, Fig. 1 shows one embodiment of my invention, in which a circular platform is centrally located with respect to a number of stages, all of said stages being substantially equidistant from the center of the camera platform and in which the camera platform may be rotated.

Fig. 2 shows a modification of my invention, wherein an annular platform supports the stages, and is free to rotate about the camera platform.

Referring now to Fig. 1, I have shown the studio room 101. A circular platform 1, mounted as a turntable, is free to rotate about its center. Mounted upon the platform is a plurality of television cameras 2. Located radially from the platform are series of stages 31, set off by partitions 5. In the figure, an octagonal form is shown to provide eight stages 31—33—35. It will be appreciated, of course, that fewer stages may be provided, for example, 6, in which the shape would be hexagonal, or more stages may be provided to afford a polygon of more than eight sides. Rearwardly of the stage from the camera position are placed rear projection screens 7, and the projectors 8 are so located as to throw the image, which is to constitute the background of the scene being televised, upon the screen 7. The actual sound broadcast may be bridged instead of picked up by the microphone. The loud speakers 11 are also located rearwardly of the screen for reproducing sound effects, which are to accompany the scene when such effects are desired or necessary.

Microphones 21 are suitably positioned on the stage 31 either by the use of floor stands or overhead booms to pick up the voice of the actors and the sound effects, if such are used. A sound monitoring studio 13 is provided, having a glass window from which the operator may see the cameramen operating the television cameras 2, and the monitoring booth 13 is equipped with a

console 65 and a monitoring loud speaker 67 to enable the operator within the studio 13 to appropriately set the levels for the outgoing sound channel accompanying the transmitted video signal from the cameras 3. It will be appreciated of course, that only one of the cameras supplies a signal for transmission at any instant, and switching from one camera to another of the plurality of cameras takes place under the control of the director. This technique is, of course, well known, and is described both in the paper entitled "Television Studio Design" by Morris and Shelby, RCA Review, July, 1937, pages 14-29, and the paper entitled "Television Studio Technic" by Protzman, Journal of the Society of Motion Picture Engineers, July, 1939, pages 26-40.

A multiple turntable 10 is also provided for furnishing from records, for example, pre-recorded sound effects to the loud speakers 61. During the production of a television show, following the televising of the scene on stage 31, the platform 1, bearing the television cameras 3, is then rotated so that the cameras bear on the scene on stage 33. When the televising of the scene on the stage 33 is completed, and it is desired to go to the next scene, the platform 1 is again rotated so that the cameras bear on stage 35 and so on. If a particular production being televised has more than eight scenes, then upon the completion of televising of the first scene on stage 31, the set may be "struck" and the scene which is to be televised following the eighth scene may then be set up on stage 31 without interfering with the televising of the scene on stage 33.

It will thus be clear that by this invention, only a minimum number of television cameras for good program production is required, and yet great flexibility is achieved in being able to smoothly effect transition from one scene to the next. It is, of course, understood that it is not necessary for the television camera channels to be open during the time the transition is being effected. As is well known, modern studio technique provides means and methods for fading the scene being televised before the switch from one stage 31 to the next stage 33 is effected, so that the images of the partitions 5 are not transmitted.

While this form of my invention is very useful, the modification in Fig. 2 still further reduces the amount of equipment necessary. In Fig. 2 the circular platform 62 carries the television cameras 61. An annular rotatable platform 87 surrounds the platform 62 and carries the stages 31, 33 and 35 radially located with respect to the center of the platform 62.

Within the studio room 99 and positioned in register with the cameras 61 is a rear projection screen 71. The screen 71 is displaced rearwardly of the stages and clear of the rotating platform 87. A rear projector 55 is positioned rearwardly from the screen 71, viewed from the camera position, and sound effect loud speakers 57 are also provided rearwardly of the screen 71. A microphone 59 is provided for picking up the sound accompanying the video signals from the cameras 61 and may suitably be carried, for example, by a microphone boom clearing the partitions 53. A sound control booth 63 is equipped with a window front 64, in order that the operator may see the cameramen on the platform 62. A console 65 is provided for mixing and controlling the volume of the various sound channels together with a monitor loud speaker 67 for the

operator's information and a multiple turntable 89 to provide the sound effects for the loud speakers 61.

In this arrangement, to change scenes requires that the platform 87 be rotated so as to bring the stages 33 and 35 sequentially in front of the cameras 61 mounted upon the platform 62. The technique during production, except for the fact that the stage platform 87 is rotated about the camera platform 62 is thus identical with the studio technique in televising the production, as described above in connection with Fig. 1. By making the stage platform 87 rotatable, it will be noted that only one projector and one rear projection screen is required, and consequently, the over-all studio equipment is reduced to a minimum.

It will be appreciated, of course, that under such circumstances, the rear projector must have its slides or film synchronized with the shifting from one stage to another. Alternatively, a second projector may be provided adjacent to the rear projector 55 and the second projector brought into action, when the stage platform 87 is rotated so as to bring the stage 33, for example, in register with the projection screen 71, instead of synchronizing the changing of the rear projection scene with the shifting of the stages.

It will, of course, be appreciated that it is not necessary, in many instances, to have rear projection screens 7 in Fig. 1 or 71 in Fig. 2, since in certain scenes, it is merely sufficient to use the conventional type of back-drop, and under these circumstances the screens 7 and 71 may be omitted.

Any suitable construction or means may be used to provide the rotating platforms 1 of Fig. 1, or the rotating platform 87 of Fig. 2.

It will thus be appreciated that the present invention makes possible in a very simple fashion smooth television production with a minimum of equipment and with a maximum of flexibility with respect to scene shifting.

What I claim is:

A television transmitting system comprising a centrally positioned platform arrangement, a plurality of television cameras carried upon said platform, a plurality of stages each representing scenes to be televised, said stages being positioned substantially adjacent to each other in annular arrangement and arranged to surround the said platform so that each of the stages is located substantially equi-distant from the center of said platform, means to rotate the annular stage members relative to the circular platform and the television cameras carried thereby to bring each of the plurality of stages successively in register with the television cameras by relative movement of the stages and the platform, a back-drop screen located substantially adjacent the outer boundary of the annular stage elements and in the path of view of the television cameras, means for projecting background images upon said back-drop to provide backgrounds for the scenes televised on the stages, means for providing auxiliary sound effects for the stages in register with the cameras, means to transmit the combined picture and sound effects from each one of the selected stages and means to limit instantaneously the picture transmission to the view seen by any one of the several television cameras.
